UNITED STATES PATENT OFFICE

REUBEN B. BENJAMIN, OF CHICAGO, ILLINOIS, ASSIGNOR TO BENJAMIN ELECTRIC MFG. COMPANY, OF CHICAGO, ILLINOIS, A CORPORATION OF ILLINOIS

CONDENSER

Application filed June 11, 1927. Serial No. 192,204.

My invention relates to a condenser construction.

One of the objects of my invention is to provide an improved condenser construction having two independently adjustable means, one of said adjustable means comprising means for causing a variation of the capacity curve which variation is greatest at the minimum capacity end of the curve, and the other adjustable means causing a variation of the capacity curve which variation is greatest at the maximum capacity end of the curve.

A further object of my invention is to provide a condenser construction having improved means for housing and shielding the condenser plates.

A further object of my invention is to provide a condenser construction which will be durable, efficient, cheap, and easy to assemble.

Further objects will appear from the description and claims.

In the drawings, in which an embodiment of my invention is shown,

Figure 1 is an elevational view of a gang condenser, parts being broken away to show the interior construction;

Fig. 2 is a section on the line 2—2 of Fig. 1;

Fig. 3 is an elevational view from the left of Fig. 1;

Fig. 4 is a detail sectional view on the line 4—4 of Fig. 2 showing the connection between the slider and actuating shaft;

Fig. 5 is a detail view of a ball retaining spring;

Fig. 6 is a detail view of an auxiliary condenser plate; and

Fig. 7 is a view of a chart showing the capacity curves obtained by various condenser adjustments.

Referring to the drawings in detail, the gang condenser shown therein comprises a plurality of condenser units arranged in tandem, a rotatable threaded shaft 1 for actuating the sliders 2 of all of these condenser units, housing means cooperating with the stators 3 for housing and shielding the condenser plates, and means whereby the maximum capacity of each unit may be varied without a corresponding variation of the minimum ca-

pacity, and means whereby the minimum capacity of each condenser unit may be varied without a corresponding variation of the maximum capacity.

Each condenser unit comprises a stator 3 and a slider 2. Each of these may be formed as a die casting of aluminum or other suitable material. The stator 3 comprises a head from which the concentric tapering condenser plates 4 extend, this head having annular recesses 5 in both of its faces to receive the circular edge of a cylindrical metal housing member 6 which, together with the head portion of the stator forms a housing and shielding member to keep foreign material out of the interior construction of the condenser and to shield the condenser plates to prevent exterior electrical fields from affecting the action of the condenser. The rotatable threaded shaft has a working fit in the stators 3 which cooperate to form bearing supports for this shaft.

Each slider may be formed as a die casting and comprises a head portion from which the concentric tapering condenser plates 7 extend. These concentric plates may be of different heights and may be designed so as to cooperate with the corresponding plates 4 on the stator to give the desired capacity curve. In order to insulate the respective slider elements each is mounted on a pair of insulating disks 8 which fit snugly in recesses in the slider. In order to provide a threaded connection with the rotatably threaded shaft the two insulating disks are mounted on a metal sleeve 9 which sleeve has an opening in which is snugly fitted a ball 10 which rides in the helical groove 11 in the shaft. In order to hold this ball snugly in engagement with the walls of the groove, a leaf spring member is provided having a ring mounting portion which fits against an annular shoulder on the metal sleeve 9 and having a spring tongue portion 13 which extends over the ball 10 and presses it radially inward. The metal sleeve 9 may be secured to the insulating disks 8 by having its ends riveted over as indicated at 14.

The condenser units may be held together and the housing members 6 held in place by means of three, longitudinally extending

screws 15 which pass through openings in the flanges of the stationary condenser elements, and are threaded into the front head 16 of the condenser. The entire gang condenser 5 may be secured to the panel of a receiving set by means of screws extending thru bosses or feet 17 on the condenser head 16.

Suitable wiring connections 18 are provided for the slider elements of the condenser 10 connected in any suitable manner to the slider as indicated at 19 and extending through eyelets 20 mounted in insulating disks 21 secured to the shell members. Each slider element is provided with an adjustable guide 15 member 22 which serves to hold the slider against rotation when the rotatable shaft is turned and, the adjacent of which enables the capacity curve obtained by rotation of the shaft 1 to be varied, the variation thus 20 effected changing the capacity curve throughout substantially the range of movement of the condenser, but providing a greater variation 25 in the maximum capacity end of the curve than in the minimum capacity end of the curve. This adjustable guide member 30 may be in the form of an arcuate plate circumferentially adjustable with respect to the casing shell, and having a longitudinally extending channel 23 in which travels a spring 35 pressed pin 24 mounted on the slider element 3. The circumferential adjustment of this arcuate plate is effected by means of a pair of screws 25 extending through slots 26 in the cylindrical shell or casing member 6 and threaded into the arcuate guide member 22. By adjusting this channeled guide member 22 circumferentially in one direction the slider may be caused to approach more closely 35 the stationary condenser element at its extreme inward movement (thus increasing the maximum capacity), and by adjusting the channeled guide plate in the other direction the slider element will be caused to approach less closely to the stator element in its extreme inward position (thus decreasing the maximum capacity). This circumferential 45 adjustment of the channeled guide plate will cause a variation in the capacity curve throughout substantially the entire range of movement of the condenser but it will produce a greater variation at the maximum capacity end of the curve than it will at the minimum capacity end of the curve as a slight difference in the distance between the 55 slider and stator has a considerable effect when the two elements are relatively close together, whereas, a slight change in the distance between the two condenser elements has a relatively small effect when the two elements 60 are relatively remote. However, the adjustment does affect the curve throughout substantially the entire range of the condenser movement as is shown by curves A and B in Figure 7. These curves correspond to 65 curves obtained by actual tests of a condenser

constructed in accordance with the disclosure in this application. Curve A shows the capacity in M. M. F. the vertical axis corresponding to dial movement in degrees on the horizontal axis with the channeled guide plate set to give the least possible capacity at the maximum capacity end of the curve (which corresponds to the extreme inward position of the slider condenser element). The curve B is the capacity curve obtained 70 when the channeled guide member is set to give the greater possible capacity at the maximum capacity end of the curve. It will be seen that the curves A and B start at practically the same point at the zero dial position, and gradually diverge as the dial position increases, until at the 340° dial position there is about 70 M. M. F. difference between 75 the maximum capacity of curve A and the maximum capacity of curve B. 80

As will be explained in detail, another adjustment is provided which also varies the capacity curve throughout substantially the entire range of movement but which, in contrast to the adjustment just described, produces a greater variation in the minimum capacity end of the curve. By a proper combining of the two adjustments the capacity curve may be adjusted within limits to vary 85 the rate of change of capacity as desired. This second adjustment, as illustrated, comprises an auxiliary arcuate condenser plate 27 which is located adjacent the periphery of the slider element 2 when the slider element is in its most distant position with respect to the stator element 3. This auxiliary condenser plate 27 may be adjusted radially in or out with respect to the slider element by means of a thumb nut 28 having a threaded engagement with a stud 29 secured to the auxiliary condenser plate 27 and extending out through an opening in the cylindrical casing shell 6. In order to guide this auxiliary plate into in and out movement and prevent the stud from turning with the nut, one edge of the auxiliary plate is caused to bear against the flange 30 on the stator element. In order to limit the inward movement of the auxiliary condenser plate a circular flange 31 is provided on the stator plate 100 with which the arcuate flange 32 on the auxiliary condenser plate comes into contact to limit its inward movement. This flange is offset with respect to the body portion of the auxiliary condenser plate in order to enable 105 the auxiliary plate to be moved sufficiently near the slider element and in order to give stiffness to the auxiliary plate. In order to move the auxiliary condenser plate inward when the thumb nut is loosened to permit 110 inward movement, a leaf spring 33 is provided, the central portion of which is apertured to permit the passage of the stud 29 on the condenser plate, and the ends of which 115

bear against the inner surface of the cylindrical casing shell.

In order to hold the rotatable shaft against end play it is provided with a collar 34 which bears against the condenser head and which is held against this head by means of a spring spider 35, the legs of which bear against the front face of the condenser head, and the central portion of which bears against a collar 36 secured to the rotatable shaft 1 by means of a set screw 37. In order to limit the rotation of the actuating shaft a stop flange 38 is secured to the collar 36, this stop flange having a stop finger 39 which engages a stop lug 40 formed integral with the condenser head.

By adjusting this auxiliary condenser plate 27 radially in or out the capacity curve obtained by movement of the slider may be varied throughout substantially the entire range of movement, but the greater variation will be obtained at the minimum capacity end of the curve as contrasted with the variation obtained by the adjustment of the channeled 25 guide member 22 which is greatest at the maximum capacity end of the curve. The reasons for the greater effect of the auxiliary condenser plate at the minimum capacity end of the curve is that in this position there is 30 the maximum overlap between the slider element and the auxiliary condenser plate. A change in the radial adjustment of the auxiliary plate 27 will cause a relatively great change in the capacity when the slider element is in its extreme out position; whereas the same adjustment of the auxiliary condenser plate will have relatively little effect when the slider element is in its extreme in position. This is indicated in curves C and 35 D in Fig. 7. Curve C indicates the capacity curve obtained corresponding to dial adjustments when the auxiliary condenser plate is in its extreme out position giving the smallest possible capacity for the low capacity end 40 of the curve (corresponding to zero dial movement). Curve D is the curve obtained when the auxiliary condenser plate is in its extreme in position giving the greatest possible capacity for the minimum capacity end 45 of the curve. It will be seen that a difference of almost 10 M. M. F. is obtained between the greatest possible minimum capacity and the least possible minimum capacity.

By a suitable manipulation of two adjustments the capacity curve may be made to start anywhere between the points E and F and to finish anywhere between the points G and H. This range of adjustment is usually sufficient to enable circuits to be tuned to give 50 the desired results after the gang condenser has been installed and connected in a radio receiving set, thus avoiding the difficulties attendant on carefully matching condensers, coils, etc.

65 I claim:

1. A condenser construction comprising a stationary element having cylindrical condenser plates and a movable element having cylindrical condenser plates cooperating with said stationary plates, manually operable means for actuating the movable element for increasing or decreasing the capacity, and adjustable means for varying the capacity curve of the condenser, comprising means whereby the capacity corresponding to the maximum capacity position of the manually operable actuating means may be varied without as great a variation of the capacity corresponding to the minimum capacity position of the manually operable actuating means. 70

2. A condenser construction comprising a stationary element having cylindrical condenser plates and a movable element having cylindrical condenser plates cooperating with said stationary plates, manually operable means for actuating the movable element for increasing or decreasing the capacity, and adjustable means for varying the capacity curve of the condenser, comprising means whereby the capacity corresponding to the maximum capacity position of the manually operable actuating means may be varied without as great a variation of the capacity corresponding to the minimum capacity position of the manually operable actuating means. 85

3. A condenser construction comprising a stationary element having cylindrical condenser plates and a movable element having cylindrical condenser plates cooperating with said stationary plates, manually operable means for actuating the movable element for increasing or decreasing the capacity, and adjustable means for varying the capacity curve of the condenser, comprising means whereby the capacity corresponding to the minimum capacity position of the manually operable actuating means may be varied without as great a variation of the capacity corresponding to the maximum capacity position of the manually operable actuating means. 90

4. A condenser construction comprising a stationary element having cylindrical condenser plates and a movable element having cylindrical condenser plates cooperating with said stationary plates, manually operable means for actuating the movable element for increasing or decreasing the capacity, and adjustable means for varying the capacity curve of the condenser, comprising means whereby the capacity corresponding to the maximum capacity position of the manually operable 100

actuating means may be varied without as great a variation of the capacity corresponding to the minimum capacity position of the manually operable actuating means, said manually operable means comprising means for moving the movable condenser element longitudinally of the axis of the cylindrical plate elements and said adjustable means comprising means for rotating one of said condenser elements about an axis extending longitudinally of the axis of the cylindrical plate elements.

5. A condenser construction comprising a stationary element having cylindrical condenser plates and a movable element having cylindrical condenser plates cooperating with said stationary plates, manually operable means for actuating the movable element for increasing or decreasing the capacity, and 10 adjustable means for varying the capacity curve of the condenser, comprising means whereby the capacity corresponding to the minimum capacity position of the manually operable actuating means may be varied without as great a variation of the capacity corresponding to the maximum capacity position of the manually operable actuating means, said manually operable means comprising means for moving the movable condenser element longitudinally of the axis of the cylindrical plate elements and said adjustable means comprising an auxiliary adjustable condenser element lying adjacent the movable condenser element when the latter is in its 25 minimum capacity position.

6. A condenser construction comprising a stationary element having cylindrical condenser plates and a movable element having cylindrical condenser plates cooperating with said stationary plates, manually operable means for actuating the movable element for increasing or decreasing the capacity, and adjustable means for varying the capacity curve of the condenser, comprising means whereby the capacity corresponding to the minimum capacity position of the manually operable actuating means may be varied without as great a variation of the capacity corresponding to the maximum capacity position of the manually operable actuating means, said manually operable means comprising means for moving the movable condenser element longitudinally of the axis of the cylindrical plate elements and said adjustable means comprising an auxiliary adjustable condenser element lying adjacent the movable condenser element when the latter is in its minimum capacity position, said auxiliary condenser element being curved to conform to the periphery of the movable condenser element and being adjustable radially with respect to said movable condenser element.

7. A condenser construction comprising a stationary element provided with condenser plates and a movable element provided with

condenser plates and two independently adjustable means for varying the capacity curve obtained by movement of said movable element, one of said adjustable means comprising means for causing a variation of the curve throughout substantially the entire range of movement and causing a greater variation in the maximum capacity end of the curve than in the rest of the curve, and the other adjustable means comprising means for causing a variation of the curve throughout substantially the entire range of movement and causing a greater variation in the minimum capacity end of the curve than in the rest of the curve.

In witness whereof, I have hereunto subscribed my name.
